(57) **CLAIM**

The ornamental design for a motorcycle tire as shown and described.

DESCRIPTION

FIG. 1 is a perspective view of a motorcycle tire showing my new design;

FIG. 2 is a front view thereof, the back view being a mirror image thereof;

FIG. 3 is a top view thereof, the bottom view being identical;

FIG. 4 is a right side view thereof;

FIG. 5 is a left side view thereof;

FIG. 6 is a fragmentary enlarged front view of the part defined by the line 6-6 of FIG. 2;

FIG. 7 is an end view taken along line 7-7 in FIG. 6; and, FIG. 8 is an end view taken along line 8-8 in FIG. 6.

The broken lines in the drawings illustrate features of a tire that are not being claimed, and form no part of the claimed design. The stippled surface shading represents the recessed portion of the claimed tread groove, having the depth as shown in FIGS. 7 and 8.
